INVENTOR,
C. A. PROULX,

BY
James J. Sheehan & Co,
ATTORNEYS

Patented Mar. 27, 1923.

UNITED STATES PATENT OFFICE.

CHARLES A. PROULX, OF WOONSOCKET, RHODE ISLAND.

BOBBIN HOLDER.

Application filed October 28, 1921. Serial No. 511,121.

To all whom it may concern:

Be it known that I, CHARLES A. PROULX, a citizen of the United States, residing at Woonsocket, in the county of Providence and State of Rhode Island, have invented new and useful Improvements in Bobbin Holders, of which the following is a specification.

My present invention pertains to bobbin holders, more particularly for use in connection with spinning and twisting machines in the manufacture of yarn, and it contemplates the provision of a device that will materially decrease the friction between the driving pulley and the driven elements and hence materially reduce the amount of power to be applied for winding the yarn on the spindle and at the same time reduce to a minimum the breakage of yarn during the spinning and winding process.

The invention further contemplates an anti-friction holder that may be used for various other purposes other than those specifically referred to above and one that overcomes many objections, such for instance, friction and unsteady rotary operation, that are present in devices now in the market.

The invention further contemplates a device that is initially and comparatively inexpensive to produce and operate and one that will outlast similar devices for the same character.

Another object of the holder is the arrangement of my novel means where the tube and its driven means are permitted a certain degree of movement or "floating" action with respect to the driven means hence decrease the amount of friction in operation.

Other objects and characteristic features of the invention will be understood from the following description and claims when the same are read in connection with the drawings, accompanying and forming part of this invention, in which:

Figure 1 is a side elevation of my novel anti-friction means as applied to a bobbin spindle.

Figure 2 is a longitudinal sectional view of the stationary spindle with my means removed.

Figure 3 is a longitudinal sectional view of the spindle tube and anti-friction means and showing the spindle in dotted lines.

Figure 4 is a sectional view of the upper cap of my anti-friction means.

Figure 5 is the drawing pulley or cap shown in section and illustrating the bearings or ball race formed interiorly thereof.

Fig. 6 is a section through the oil cap.

Figure 7 is a view showing a side elevation of a portion of the tube and the driving cap thereof.

Figure 8 is an inverted plan view of Figure 7.

Figure 9 is a detailed longitudinal section of the sleeve of the device, and showing the bottom cone properly positioned thereon.

Figure 10 is an inverted plan view of Figure 5.

Figure 11 is a side elevation of the bottom ball cone.

Figure 12 is an inverted plan view of the cone shown in Figure 11, and

Figure 13 is a sectional view taken on the plane indicated by line 13-13 of Figure 9 and looking in the direction of the arrow.

Figure 14 shows a modified form of holder that is rolled at its ends and at a point intermediate the ends.

Figures 15 and 16 are modified oil retainers and caps.

I have illustrated my device as applied to the spindle of a spinning or twisting machine but this is done merely for the purpose of illustration as the device may be used in connection with any machinery or for all purposes to which it is applicable.

In the drawings I illustrate a bobbin spindle 1 having the base or lower portion 2 and the kerfs 3 arranged in the outer surface of the base 2 and at its lower end the spindle is provided with the tapered lower end 4 and the upper pointed end 5 as shown.

This spindle and its construction are not of the essence of my invention.

This bobbin 1 is mounted in a perpendicular manner and properly supported in stationary manner in the machine or other support.

A bobbin holder or tube 7 is adapted to surround the spindle 1 and is operative in a vertical and rotatable manner with respect

to the spindle. The vertical movement is produced for building up the yarn on the holder and such vertical movement is produced in any of the well-known manners and as this forms no part of my invention illustration and description thereof is eliminated.

The holder is preferably a tubular column as shown and is adapted to be pressed 10 or threaded at its lower end into a driven cap portion 9 having an integral collar 8 and also having the lugs 10 on its lower face.

I have illustrated but two of the lugs 10 but do not wish to confine myself to any 15 particular number thereof.

This cap or driver 9 for the tube 7 is provided with the lugs or projections 10 in order that said lugs may take into registering slots 11 of the pulley or member 12, and the 20 cap 9 is machined on its outer surface so as to allow a "floating" or sidewise movement of the cap with respect to the spindle, and thus eliminate friction between the spindle and tube 7 incidental to rotation of the tube 25 about the spindle.

The pulley or cap 12 is a very important feature of my invention and threaded or pressed on the upper end thereof is a cap 14 that is also interiorly machined to permit 30 floating of the tube 7 and cap or driver 9 to eliminate friction between the spindle and said elements.

Manifestly rotation of the pulley 12 will be attended by rotation of cap 14. This cap 35 14 is provided with the integral portion 15 and collar lugs, or flange 13 and in its upper surface oil apertures may be provided in order to permit of introduction of oil into the floating space within the cap 14.

40 As shown in Figures 5 and 10 the pulley 12 is provided with an upstanding portion 16 whereby a flange is formed around the pulley and by reference to Figure 3 it will be apparent that the cap 14 bears against 45 the flange or pulley 12. This cap 14 is by preference interiorly machined to assist in the floating movement of the tube 7 and its appurtenances.

At its lower end the pulley 12 is provided 50 with a portion 17 similar to the portion 16 and on its outer surface the pulley 12 is machined as indicated by 23. Manifestly the machined portion may be round to receive a round belt or may be flat to receive a flat 55 belt. In this connection I might state that the machined surface 23 may be of any type compatible with its purpose and I do not wish to be confined to any particular shape of machined surface as it is proposed to use 60 the same in connection with any shape, size or style of belt 24.

The pulley 12 is provided with the chambers 25 and 26 that act in conjunction with certain other elements of the invention, as

65 a ball race for the balls 27 and pressed or threaded on the lower end of pulley 12 and abutting the portion 17 thereof is an oil cap 18 having the base 19 and formed interiorly of the cap and extending parallel with the outer upstanding portion thereof is a wall 20. A chamber is formed circumferentially 70 of the cap by the wall 20 and in said chamber, I insert suitable packing 21 in the form of a felt washer and superimposed on the felt washer 21 is a washer 22 (Figure 3). 75

In order to form with the upper chamber 25 of the pulley 12, the race-way for the upper balls 27, I provide the cone 28 and to form with the lower chamber 26 of the pulley 12 the raceway for the lower balls 27, I 80 provide a cone 29. These cones are pressed or otherwise secured to the sleeve having the shoulder 32 of my novel device and the sleeve 31 may when occasion arises be provided with oil holes to receive oil direct 85 from the spindle 1 and the sleeve 31 is further adapted to be pressed on a bushing 31 and said sleeve may be provided with the threads to receive cones 28 and 29 or said cones may be pressed on the sleeve in the 90 discretion of the manufacturer.

Provided longitudinally in the sleeve 31 is a key-way slot 33 and arranged on the sleeve is a lock-washer 34 having a projection or tongue 35 that enters the key-way 95 slot 33 and said lock-washer 34 is also provided on its outer peripheral surface with a series of notches 36. This latter provision is made in order to permit the tongue 37 of the cone 29 to enter one of the notches 36 of lock-washer 34 and thereby lock these elements to each other. 100

The threads at the lower end of the sleeve 31 are adapted to receive a threaded collar 38 and extending therefrom is a pin 39 having the downwardly directed portion. This pin at its inner end forms a washer and may be provided with a notch to enter the key-way slot when occasion demands. 105

A cone shaped cap 40 is disposed below 110 the collar 38 and is provided with the member 41. This cap 40 as well as collar 38 form no part of my invention but are suggestive of elements that may be used in connection with the device. 115

It will be gathered from the foregoing that the sleeve 31, cones 28 and 29, lock-washer 34 and bushing 30 are connected with each other whereas the pulley is independently rotatable with respect to these elements and because of the slots 11 and members 10 the tube 7 and cap 9 will rotate in unison with the pulley 12. 120

It will be further manifest that the slight floating of the elements 7 and 9 on spindle 1 and within cover or cap 14 reduces to a minimum the amount of friction and thus the power to be applied to operate the pul- 125

ley and its complementary elements is very slight compared with the cost of operation of devices for like purposes.

The construction illustrated permits of a very slight engagement of the spindle and column of the tubing and this naturally decreases friction which tends to permit of a steady and even winding and unwinding of the yarn on the bobbin positioned on the tubing.

In the practical use of my novel anti-friction means in connection with bobbins the bobbin or spool as well as other elements of the device are raised and lowered by means foreign to this invention incident to the building up of the yarn on the spool. It will be seen that when the spool and tubing are rapidly rotated by pulley 12 the said operation will not only be frictionless to a great degree but will also be even at all times and this prevents the exertion of too much pressure on the yarn at certain times and the consequent breaking of the yarn.

The device when used on spinning machines requires little or no attention and because of its construction and arrangement will withstand a great amount of rough usage without getting out of order. The pulley moreover, reduces the strain on the belt which in itself is a great item of saving and because of its construction it may be employed on any character of machine or work to which it is applicable.

I have endeavored to set forth the construction and operation of my device as applied to a spinning machine or the like but in this connection I would distinctly have it understood that the construction of the anti-friction pulley constitutes the essential elements of my device.

In practice any form of locking means for the sleeve 31 and cone 29 may be employed and in the future practice of the invention such change or modifications in the size and relative arrangement of parts may be made as fairly fall within the scope of my appended claims.

The holder shown in Figure 14 comprises the tubular portion *a* that is rolled at its lower end *b* and may also be rolled in the longitudinal center of the tube as shown, and this will produce a running fit of the spindle and holder at certain points and thus relieve friction throughout the entire length of the spindle where it is covered by the holder.

When desired I may substitute the cap 40^a comprising the cover provided with the oil apertures and interposed beneath the cap is 60 felt 41^a or other suitable material.

Having described my invention, what I claim and desire to secure by Letters Patent is:—

1. In anti-friction means for bobbin

holders, the combination of a spindle, a bushing surrounding a portion of the spindle, a sleeve adjacent the bushing, a longitudinal key-way slot formed in the sleeve, a cap secured to the lower end of the sleeve, notches formed in the cap, and a closure 65 threaded on the sleeve, a washer arranged in the closure, a cone having a projection that takes into one of the notches of the cap; said closure being arranged on the sleeve, a locked washer interposed between the cone and cap and having a tongue that enters the key-way slot, a pulley surrounding the sleeve and movable independently thereof, chambers arranged interiorly of the pulley, a cone secured to the upper end of the sleeve 70 within one chamber of the pulley, anti-friction balls arranged within the chambers of the pulley and bearing on the cones, a cap arranged on the lower open end of the pulley, slots formed in the upper face of the pulley, a cap having projections that take 75 into the slots, a tube that surrounds the spindle and secured to the cap; said cap and tube being so constructed and arranged that they float with respect to the spindle and pulley, 80 and a cap arranged on the opposite open end of the pulley and surrounding the cap of the tubing.

2. In a pulley, the combination of a machined outer surface, slots formed in the upper end of the pulley, race-ways formed in the pulley, a sleeve surrounded by the pulley, cones arranged on the sleeve and movable therewith, a cap secured to the sleeve, locking means arranged on the sleeve and 90 means for securing one cone to the locking means, and anti-friction means arranged in the pulley.

3. In means for the purpose set forth, the combination of a bushing, a sleeve secured thereto, a slot formed in the sleeve, an oil cap arranged on the sleeve, a washer arranged on the sleeve and secured thereto, a cone secured to the sleeve and washer, a second cone arranged on the sleeve, a pulley surrounding the sleeve, race-ways formed between the interior of the pulley and the cones; said pulley being independently rotatable with respect to the sleeve, slots 105 formed in one surface of the pulley and means adapted to rest in the slots in a comparatively loose manner, whereby rotation of the pulley will be attended by steady rotation of said means.

4. In a device for use in connection with a bobbin winding and spinning machine, the combination of a spindle, a tube surrounding the spindle, a driving cap arranged on the tube, projections formed on the cap, a pulley arranged beneath the cap and having slots that receive the projections of the cap; said projections being comparatively smaller 115 in width and depth with respect to the slots,

a cap arranged on the lower end of the pulley, chambers produced by the interior construction of the pulley, a sleeve surrounding the spindle and movable independently of the pulley and spindle, members secured to the sleeve and locking means arranged within the pulley and cap, substantially as and for the purpose set forth.

In testimony whereof I have hereunto set my hand in presence of two subscribing ¹⁰ witnesses.

CHARLES A. PROULX.
